UNITED STATES PATENT OFFICE

150,696

DESIGN FOR A FINGER-SHAPED THIMBLE

Claude M. Howser, Santa Barbara, Calif., assignor to California Thimble Corporation, a corporation of California

Application December 16, 1946, Serial No. 135,560

Term of patent 14 years

(Cl. D3—19)

To all whom it may concern:

Be it known that I, Claude M. Howser, a citizen of the United States, residing at Santa Barbara, in the county of Santa Barbara and State of California, have invented a new, original, and ornamental Design for a Finger-Shaped Thimble, of which the following is a specification, reference being had therein to the accompanying drawing, forming part thereof, in which:

Figure 1 is an enlarged perspective view of the finger-shaped thimble, showing my new design.

Figure 2 is a view in side elevation.

Figure 3 is another enlarged perspective view of the thimble, looking at the outer end thereof.

I claim:

The ornamental design for a finger-shaped thimble, as shown.

CLAUDE M. HOWSER.
